FIG. 3.

Owen H. Spencer
Inventor

UNITED STATES PATENT OFFICE

OWEN H. SPENCER, OF INDIANAPOLIS, INDIANA

ENGINE MANIFOLD AND MEANS FOR ATTACHING SAME

Application filed April 26, 1929. Serial No. 358,365.

This invention relates to manifolds of that class adapted for use in connection with internal combustion engines and one feature of the invention is the provision of an intake, exhaust and air conveying manifold in connection with the cylinders of the engine.

A further feature of the invention is the provision of a common means for attaching all of said manifolds to the engine.

10 A further feature of the invention is in so constructing and applying the attaching means that any one of the cylinders or heads therefor may be disconnected and independently removed from their respective points 15 on the engine without dismantling the manifolds.

A further feature of the invention is in so constructing the device that the head of the cylinder may be removed without disturbing 20 or disarranging the adjustment of the valve operating mechanisms.

25 A further feature of the invention is in so positioning the bolts for attaching the manifolds to their respective parts that the number of bolts required will be reduced to a minimum.

A further feature of the invention is in so positioning certain of the securing bolts that the clamping strain thereon will be directed 30 edgewise against one wall of the manifolds, thus obviating the possibility of cramping or bending the parts of the manifolds.

35 A further feature of the invention is in so positioning the bolts with respect to ports of the manifolds, that the clamping strain against the contacting parts of the manifolds will be uniformly distributed over the contacting surface.

40 Other objects and advantages will be hereinafter more fully set forth and pointed out in the accompanying specification.

In the accompanying drawings which are made a part of this application,

45 Figure 1 is a side elevation of the upper portion of an engine with parts shown in section.

Figure 2 is a horizontal sectional view as seen along line 2-2, Fig. 1.

50 Figure 3 is a vertical transverse sectional view thru the engine.

Referring to the drawings in which similar reference numerals designate corresponding parts thruout the several views, 1 indicates the crank case of an engine, upon which are mounted a plurality of cylinders 2, on 55 which are mounted cylinder heads 3.

The cylinder heads 3 are each provided with an intake port 4 and an exhaust port 5, with which cooperate respectively, ports 6 of an intake manifold 7 and port extensions 60 8 of an exhaust manifold 9, the ports 6 having flanges 10 surrounding the same, while the port extensions 8 are provided with flanges 11.

The body of the exhaust manifold is also 65 provided with a plurality of exhaust ports 12, one for each cylinder 2, which communicate with the lower end of the cylinder, said exhaust ports 12 being so arranged that a line drawn horizontally thru the centers 70 thereof will be at substantially the same height as the bottom wall 13 of the manifold 9. The ports 12 are adapted to register with exhaust openings 14 at the lower ends of the cylinders. 75

Positioned on the opposite sides of the cylinders 2 from the exhaust manifold 9, is an air inlet manifold 15, which communicates with the cylinders 2, thru ports 16 and in order to clamp the exhaust and air manifolds in 80 position over the ports 12 and 16, bolts 17 are extended transversely between the cylinders and thru parts of the manifolds 9 and 15, preferably one bolt between each pair of cylinders. The bolts 17 are so arranged with 85 respect to the exhaust manifold that they will pass thru bores 18 in the wall 13 and substantially in line with the axial centers of the exhaust ports 12, thus leaving a smooth uninterrupted passage for the exhaust products thru the manifold. The bolts 17 pass substantially centrally thru the manifold 15 so that the pressure applied by tightening the bolts, will be equally and uniformly distributed around the ports of the respective manifolds and the pressure against the exhaust manifold will be directed edgewise against the bottom wall 13, so that the walls of the exhaust manifold will not buckle or be sprung 95 by the tightening of the bolts. By placing 100

the bolts substantially in axial alignment with the exhaust ports 12, the pressure of the manifold 9 against the end walls of the exhaust ports 12 will be uniform throughout the diameters of said exhaust ports. As shown in Fig. 2, the bolts 17 pass thru the outwardly disposed bosses 19 which prevent the walls of the air manifold 15 buckling or bending.

In addition to the bolts 17 for attaching the exhaust manifold to the cylinders, the flanges 11 on the extensions 8 are locked in position under the exhaust ports 5 of the heads 3, and the flanges 10 of the intake manifold 7 locked in position over the intake ports 4 by extending bolts 20 between each pair of intake and exhaust ports of each head 3, washers 21 engaging the under faces of the flanges 10 and 11, while nuts 22 are threaded onto the ends of the bolts 20, which, when tightened will lock the flanges securely against the faces of the ports 4 and 5. As best shown in Fig. 2, the bolts 20 are in substantial alignment with the vertical centers of the ports 4 and 5, so that it will require but one bolt for each set of ports.

By attaching the manifolds in this manner the joints between the various ports and between the heads and the cylinders, may be ground joints, thus dispensing with gaskets at these points, in which event, the heads may be removed from the cylinders without disturbing the adjustments of the valve operating rods, etc.

Each cylinder head 3 is provided with a valve 23, which controls the admission of gaseous fuel to the cylinders, each valve having a rocker arm 24 cooperating therewith, which is in turn operated by means of a rod 25, a tappet 26 and a cam 27, as is usual, and suitable adjusting means 28 being provided between the rocker arm 24 and rod 25. Each head 3 is also provided with a valve (not shown) for controlling the exhaust port 5 therein, said valves being operated in the same manner as the valves 23 and having the same adjusting mechanisms thereon for the rocker arms and operating rods therefor.

To guard against any possibility of the manifold 15 shifting down out of alignment with the ports 16, one or more lips 29 are conveniently formed on the crank case 1 for receiving the pintles 30 of posts 31, the upper ends of the posts engaging the lower face of the manifold 15, which also prevents the manifold dropping down, when the bolts 17 are loosened.

With this form of device it will be readily seen that each entire cylinder with the head thereon, may be removed without disturbing or disarranging the manifolds or cylinders, as by loosening the bolts 17 at each side of the particular cylinder to be removed and removing the bolt 20 of that particular cylinder, the entire cylinder may be lifted out or returned to position without disturbing

any of the other parts of the engine. Likewise, each of the cylinder heads may be removed by disconnecting the respective bolt 20, without disarranging the manifolds or their connections with the other cylinders.

It will likewise be seen that the operation of assembling or disassembling the engine will be greatly facilitated, as the number of bolts required to connect the manifolds to the engine is reduced to a minimum.

While the description and drawings illustrate in a general way certain instrumentalities which may be employed in carrying the invention into effect, it is evident that many modifications may be made in the various details without departing from the scope of the appended claims, it being understood that the invention is not restricted to the particular examples herein described.

I claim as my invention:

1. The combination with the cylinders of an engine and manifolds therefor, of bolts for clamping a pair of manifolds to said cylinders, said bolts connecting solely with said manifolds and passing between said cylinders without contact therewith.

2. The combination with the cylinders of an engine and an exhaust manifold and an air manifold therefor, of means for binding the exhaust and air manifold to the cylinders without engaging any parts of the binding means with the cylinders comprising bolt means passing between the respective cylinders with their ends engaging said manifolds.

3. The combination with the cylinders of an engine and manifolds therefor, of means extending between the pairs of cylinders and engaging said manifolds for binding said manifolds against said cylinders.

4. The combination with the cylinders of an engine having an exhaust and an air inlet port adjacent their lower ends, and a pair of manifolds adapted to cooperate with said exhaust and air ports, of means extending between said cylinders for clamping said manifolds in position over their respective ports, and means for preventing buckling of the walls of the manifolds when the clamping means is applied.

5. The combination with the cylinders of an engine, having exhaust ports in the lower portions thereof, of an exhaust manifold having ports adjacent one wall thereof for cooperating with the ports of the cylinders, the port containing wall of the manifold between said port openings being on a common level, the axial centers of said manifold ports being substantially central with the medial line of the port containing wall of the manifold.

6. The combination with an exhaust manifold having ports therein, the centers of which are substantially on a line with the medial line of the bottom wall of said manifold, of bolts for clamping said manifold in

operative position, said bolts passing thru the lower wall of said manifold substantially in line with the centers of said ports, whereby the clamping strain of the bolts will be directed edgewise against said lower wall and no part of the covering for the bolts project above the bottom wall.

7. The combination with the cylinders of an engine, of manifolds on opposite sides of 10 said cylinders, means extending between the cylinders and from one manifold to the other for clamping said manifolds in engagement with said cylinders, and means for preventing said manifolds dropping down when the 15 clamping means is loosened.

8. The combination with a manifold having ports therein adjacent one wall thereof, the centers of said ports being substantially on a line with the medial line of said wall, of 20 bolts for clamping said manifold in operative position, said bolts passing through said alining wall and substantially in line with the centers of said ports with no part of the covering for said bolts projecting beyond the 25 inner face of said wall.

9. The combination with a cylinder, and a removable head for said cylinder having ports therein with their outer ends projecting downwardly, of manifolds for cooperation 30 with said ports, and means for drawing said manifolds upwardly and bind them in engagement with said port ends, whereby when said securing means is released said head may be removed from the cylinder without disturbing the position of said manifolds.

In testimony whereof, I have hereunto set my hand on this the 25th day of March, A. D. 1929.

OWEN H. SPENCER.
